9 Claims. (Cl. 102—18)
(Granted under Title 35, U.S. Code (1952), sec. 266)

This invention relates to mine firing mechanisms of the electromagnetic inductance type in which a changing magnetic field is employed to fire the mine and in which the possibility of exploding the mine by an airborne mine sweeping operation is remote. More specifically, the present invention contemplates the provision of means for detecting, at predetermined spaced intervals, changes in a magnetic field adjacent the mine and in which the mine is fired when two such changing conditions are detected within these intervals.

The types of induction mines heretofore devised have been swept by airborne mine sweeping apparatus comprising a sweep coil secured to the airplane and energized by a strong electrical current thereby to set up a magnetic dipole capable of operating the mine firing mechanism of the mine as the aircraft traverses the mine flying at a low altitude.

In the system of the present invention, the mine firing mechanism includes certain detecting, selecting and time delay elements in combination with the field sensing device whereby the detonation of the mine is effected when a second change in the magnetic field is sensed by the sensing coil within a predetermined interval of time following a brief interval during which the mine is momentarily unarmed after a first change in the magnetic field has been detected and in which the mine is not fired by a second change of magnetic field occurring during the brief unarmed interval or after the aforesaid predetermined interval of time has expired. The arrangement of the present invention, moreover, in providing an unarmed or dead interval of time immediately following the first detection of a magnetic change prevents a second or firing actuation of the mine firing mechanism in response to the sweep signal received from the fast moving aircraft whereas a change of the magnetic field caused by the movement of a steel vessel, or any vessel having considerable amount of magnetic material therein moving past the mine, causes the field sensing and detecting mechanism to set into operation certain elements of the mine firing mechanism whereby the mine is fired in predetermined time delayed relation with respect to the detection of a second changing magnetic condition within a predetermined time interval immediately following the dead interval.

By reason of the selecting and time delay elements and circuit connections therebetween, the detonation of the mine by a single airborne mine sweeping operation is prevented. In accordance with a preferred embodiment of the invention the mine is momentarily disarmed by rendering the sensing and detecting mechanism unresponsive to a changing magnetic field for a brief period of time immediately following the detection of a changing field condition and thereafter a second time interval is measured within which a second changing condition of the magnetic field is effective to fire the mine. This is accomplished by charging a condenser slowly through a resistance element from a source of electrical potential within the mine, as will more clearly appear as the description proceeds.

One of the objects of the present invention is to provide a new and improved magnetic mine firing mechanism of simple and rugged construction which is selectively responsive to a changing magnetic field which will be economical to manufacture and which possesses the de-

sired qualities of reliability and efficiency in use and operation.

Another object is to provide a mine firing device of the above general character having new and improved means for measuring a predetermined interval of time immediately after a changing magnetic field condition has been detected during which the mine may not be fired.

Another object is to provide a mine firing device having new and improved means for measuring a predetermined interval of time immediately following the detection of a changing magnetic field adjacent thereto during which the mine is disarmed and immediately thereafter arming the mine whereby the mine may be fired only in response to a changing condition of the magnetic field detected during a predetermined interval of time immediately following the interval during which the mine was disarmed.

Another object resides in new and improved means responsive to a changing magnetic field for comparing the continuance of the changing field with a predetermined interval of time and selectively firing an explosive in accordance with the results of such comparison.

Still further objects, advantages and improvements will be apparent from the following description taken in connection with the following drawing, of which:

FIG. 1 is a view of the mine employing the mine firing circuit of the present invention and showing an airborne sweeping operation thereof, and

FIG. 2 is a circuit diagram showing in schematic form a complete system suitable for use with the present invention according to a preferred embodiment thereof.

Referring now to FIG. 1 of the drawings for a more complete understanding of the invention there is shown thereon a mine 2 planted on the bed of a body of water and subjected to a sweeping operation by an aircraft 3 having a sweep coil 4 secured thereto. The sweep coil is connected with a source of electric current thereby to set up a magnetic field of sufficient strength to be detected by the mine as the aircraft moves thereacross. The mine is provided with the mine firing mechanism of the present invention and is not swept in response to the sweeping operation.

In FIG. 2 is shown a complete system employing the present invention in which the mine is fired in response to a changing magnetic field detected within a predetermined interval of time immediately following a period in which the mine is momentarily disarmed in response to a first detection of the changing magnetic field. The system comprises a sensitive control relay D of any type suitable for the purpose such, for example, as a relay known in the art as a "Sensitrol" and having an operating winding DO adapted to actuate a movable contact element into engagement with either one of a pair of contacts selectively in accordance with the direction of flow of the operating current through the winding DO. The relay remains in the operated condition with the movable element thereof in engagement with the selected contact until the movable element is forcibly restored to an initial unoperated position intermediate the pair of contacts by the energization of a reset magnet DR. The operating winding DO of relay D is connected to a pickup or search coil SC preferably having a core of magnetic material 5 therein to increase the pickup power of the coil whereby the relay D is adapted to be operated by the voltage induced within the search coil in response to a changing condition of the magnetic field adjacent thereto. The movable contact element of relay D is electrically connected to and controls the operation of a control relay R having a normally open contact adapted to be closed as the relay operates. Relay R is provided with any suitable means such, for example, as a copper slug or the dash pot 6 illustrated to render the relay slow in releasing

for a purpose which will be more clearly apparent as the description proceeds. A time delay device TD is also provided in which the operating magnet thereof is adapted to attract a rotatable armature 7 and cause it to move away from a stop 8 against which it is yieldably urged by a spring 9. The rate of movement of the armature 7 is retarded by an escapement mechanism such that the operating magnet of the time delay device is required to be energized continuously for a predetermined period of time such, for example, as 10 seconds before the armature 7 has moved through a distance sufficient to close the normally open contacts 11 of the device. The time delay device is connected in series with the winding of relay R and is set into operation when the operating circuit to relay R is closed. In the event that the operating circuit to relay R and the timing device does not remain closed for the period of time required to close contacts 11, the interruption of this circuit causes armature 7 to be quickly restored by the spring 9 to the initial unoperated position thereof in engagement with the stop 8.

The power required for the operation of relay R and the time delay device TD is obtained from a battery B, the circuit including a pair of contacts on an arming clock indicated generally by the numeral 12. The arming clock may be of any type suitable for the purpose in which the clock is set in operation by a hydrostatic device actuated by the pressure of the water within which the mine is planted, as is well known in the art to which the present invention pertains.

Whereas in FIG. 2 there is shown an arming clock 12 having a pair of normally open contacts adapted to be closed within a predetermined period of time such, for example, as 15 minutes after the mine has been planted it will, of course, be understood that various other well known arrangements may be employed for arming the mine such, for example, as an arrangement in which the arming contacts are closed by a hydrostat when sufficient time has elapsed for a soluble washer associated therewith to become dissolved and thereby permit movement of the hydrostat.

The mine firing mechanism of FIG. 2 also includes a battery B1 connected in series with battery B for charging a condenser C through a pair of resistance elements 13 and 14. The ohmic value of the resistance elements 13 and 14 bears a predetermined relation with respect to the capacity of condenser C such that a predetermined period of time such, for example, as 60 seconds is required to charge the condenser C fully after the condenser has been discharged by the operation of relay R. The condenser C is employed to provide a source of stored electrical energy sufficient to operate the reset magnet DR of relay D as the contacts of relay R are closed and to maintain the magnet DR operated for a predetermined interval of time such as two seconds. This is accomplished by providing a winding of the reset magnet DR of sufficient resistance to prevent discharging the condenser to a value below the hold valve of the magnet DR during this interval. Each time the reset magnet DR is operated by relay R the charge on condenser C is exhausted and does not build up again until a predetermined period of time such, for example, as 60 seconds has elapsed after relay R has released whereby, in the event that relay D is operated by the voltage from the pickup coil in response to a changing magnetic field before the charge on the condenser has built up to a value sufficient to operate the reset magnet DR, relay D remains operated for a period of time sufficient to cause contacts 11 of the time delay device TD to close and fire the electroresponsive detonator 15.

The operation of the system will best be understood by consideration of a specific example. Let it be assumed by way of example that the mine has been planted within the body of water and that the contacts of relay D are moved to the closed position thereof during the planting operation.

When the mine has been planted for a period of time

sufficient for the contacts of the arming clock 12 to close, a circuit is completed from the positive terminal of battery B by way of conductor 16, contacts of arming clock 12, conductor 17, contacts of relay D, conductor 18, winding of relay R, conductor 19, operating winding of time delay device TD, from whence the circuit is continued by way of conductor 21 to the negative terminal of battery B thereby causing relay R to operate and the time delay device TD to be set into operation. As armature 22 of relay R is moved into engagement with its contact, a circuit is closed from the positively charged plate of condenser C by way of conductor 23, reset magnet DR of relay D, conductor 24, make contact and armature 22 of relay R, conductor 25, and thence to the negative plate of condenser C. When this occurs the charge on condenser C causes the reset magnet DR to operate and forcibly restore the moving contact element of relay D to a position intermediate the pair of contacts of the relay and disengaged therefrom, the moving contact element being locked in this position until the reset magnet is released. During this period of restraint of the relay D the mine is disarmed.

As the contacts of relay D are disengaged, the operating circuit to relay R and time delay device TD is interrupted and the time delay device TD immediately restores to normal. Armature 22 of relay R, however, is prevented from disengaging its make contact until a period of time sufficient to discharge condenser C such, for example, as four seconds has elapsed by reason of the provision of the dash pot 6 thereon. As armature 22 of relay R is disengaged from its make contact, the operating circuit for reset magnet DR is interrupted, the reset magnet is released, the restraint of the movable element of relay D is removed and relay D is responsive to a change in the ambient magnetic field detected by the pickup coil SC. The mine is now armed. The release of relay R at armature 22 thereof removes the discharge load from condenser C and the condenser now receives a charging current from batteries B and B1 by way of resistances 13 and 14. When condenser C has become fully charged the charging current from batteries B and B1 ceases.

Let it now be assumed that a steel vessel or a vessel having a preponderance of magnetic material therein subsequently passes above the mine. As relay D operates in response to the first changing condition of the magnetic field caused by the moving vessel, a circuit is closed to operate relay R and set the time delay device TD into operation. As armature 22 of relay R engages its contact, condenser C is connected to the reset magnet DR over a closed circuit and the reset magnet operates thereby restoring and locking relay D with the movable contact thereof in the original unoperated position. Relay D remains locked until the charge on condenser C has decreased sufficiently to release the magnet DR. While relay D is thus locked, the mine is disarmed and unresponsive to changes in the magnetic field.

As relay D releases, the operating circuit to relay R and the time delay device TD is interrupted and the time delay device is restored to normal by the spring 9. Relay R releases in time delayed relation with respect to the interruption of the operating circuit thereto by reason of the provision of the dash pot 6 aforesaid or other time delay means provided thereon and the reset magnet DR is disconnected from condenser C. When this occurs the load is removed from condenser C and the condenser begins to charge. The removal of restraint from relay D as magnet DR releases renders relay D responsive to a second signal received from the pickup or search coil SC thereby rearming the mine.

It may now be assumed that the relay D operates a second time by reason of the changing magnetic field caused by the vessel moving above the mine and detected by the pickup coil SC. As the contacts of relay D are engaged, relay R operates and the time delay device TD is set into operation. As armature 22 of relay R is moved to closed position, condenser C is connected to the reset

magnet DR but the reset magnet does not operate by reason of the fact that insufficient time has elapsed since the condenser was discharged by relay R, as relay D first operated in response to the detection of the changing magnetic field of the vessel by search coil SC, for the condenser C to have acquired a charge of sufficient strength to operate the reset magnet. Relay D, therefore, remains operated and at the expiration of 10 seconds, in the assumed case, contacts 11 of the time delay device TD are closed by armature 7 thereof. When this occurs a circuit is closed from the positive terminal of battery B by way of conductor 16, closed contacts 12 of the arming clock, conductor 26 to the electroresponsive detonator 15, from whence the circuit is continued by way of conductor 27, contacts 11 of the timing device TD, and conductor 21 to the negative terminal of battery B thereby operating the detonator 15 and firing the mine beneath a vulnerable portion of the vessel.

The effectiveness of the mine firing circuit herein disclosed in causing the mine not to be fired in response to a mine sweeping operation will best be understood by consideration of a specific example in which the mine sweeping operation is performed from an aircraft in flight. In this case the operation of relay D, as the aircraft passes over the mine, causes relay R to be operated. As armature 22 of relay R engages its contact, relay D is locked in the unoperated position thereof by the reset magnet DR thereby disarming the mine for two seconds during which the aircraft will have moved to a position beyond the mine such that the magnetic sweep therefrom is not effective to cause relay D to reoperate when the mine is rearmed by the release of magnet DR.

Obviously many modifications and variations of the present invention are possible in the light of the above teachings. It is, therefore, to be understood that within the scope of the appended claims the invention may be practiced otherwise than as specifically described.

The invention herein described and claimed may be manufactured and used by or for the Government of the United States of America for governmental purposes without the payment of any royalties thereon or therefor.

What is claimed as new and desired to be secured by Letters Patent of the United States is:

1. In a submarine mine of the character disclosed arranged within a magnetic field, a relay, means including said relay for detecting a plurality of changing magnetic conditions within said field, electroresponsive means for resetting the relay to an initial unoperated condition, said resetting means being constructed and arranged to operate on condenser discharge and maintain the relay in said initial condition until the resetting means has been deenergized, a normally charged condenser, a condenser discharge circuit including said resetting means, a slow releasing relay operatively connected to the first-named relay and adapted to be operated thereby as the first-named relay operates, means on said slow releasing relay for closing said discharge circuit thereby to operate said resetting means while the condenser is being discharged, a time measuring device connected to and operated by the first-named relay constructed and arranged to measure an interval of time in excess of the resetting time of the first-named relay to said initial condition, means for charging said condenser, a firing circuit, and means on said time measuring device for closing said firing circuit when the time measuring device has been continuously operated by the first named relay for said predetermined interval of time while the condenser is discharged.

2. In a submarine mine of the character disclosed arranged within a magnetic field, an electrical relay, means including said relay for detecting a plurality of changes in magnetic conditions within said field, means controlled by said detecting means for rendering the detecting means unresponsive to a changing condition of the field for a predetermined period of time after a change in magnetic

condition has been detected, said last-named means including a condenser, a normally open discharge circuit for said condenser and means controlled by said relay for closing the discharge circuit in response to the operation of said relay for a said period of time, means for charging said condenser during a predetermined interval of time after said discharge circuit has been interrupted, a device controlled by said detecting means for measuring a second predetermined period of time, a firing circuit, and means on said time measuring device for closing said firing circuit when the device has been continuously operated for said second predetermined period of time.

3. In a submarine mine of the character disclosed arranged within a magnetic field, means for detecting a plurality of changes in the magnetic conditions within said field, a normally charged condenser, relay restoring and locking means controlled by said condenser for rendering the detecting means unresponsive to a change in condition within the field for a predetermined interval of time after a change in condition has been detected, means including said condenser for measuring a second interval of time immediately following said first time interval, and means controlled by said condenser for rendering said restoring and locking means ineffective to restore and lock the detecting means as a change in the magnetic condition within the field is detected during said last-named interval.

4. In a submarine mine of the character disclosed arranged within a magnetic field, means for detecting a plurality of changes in magnetic conditions within said field, a normally charged condenser, means controlled by said detecting means for discharging the condenser as a change in magnetic conditions is detected, means connected in the discharge path of said condenser for rendering the detecting means ineffective to detect a change in magnetic conditions while the condenser is being discharged, means for charging the condenser, and means controlled by the detecting means for causing said mine to explode when a changing condition within said field is detected while the condenser is being charged.

5. In a submarine mine of the character disclosed, the combination of an electrical relay, means including said electrical relay for detecting variations in the magnetic field adjacent the mine, a normally charged condenser, means operatively connected to said relay for discharging said condenser as a variation in the magnetic field is detected, means operatively connected to the condenser for locking the relay in an unoperated condition while the condenser is being discharged whereby the detecting means is ineffective to detect a variation in the magnetic field for a predetermined interval of time after a variation therein has been detected, means for charging said condenser at the expiration of said period of time, a device operated by said relay for measuring a second time interval when a variation in said field is detected while the condenser is being charged, a mine firing circuit, and means on said device for closing said mine firing circuit at the completion of said second time interval.

6. In a submarine mine of the character disclosed disposed within a magnetic field on the bed of a body of water, mine firing mechanism, means included within said mine firing mechanism for sensing in succession changing magnetic conditions within said field, a relay operatively connected to said sensing means and adapted to be operated thereby, a source of electrical power, a condenser, a charging circuit for said condenser operatively connected to said source of power and having resistance means therein for causing the condenser to be slowly charged, a discharge path for said condenser, relay restoring and locking means connected in said discharge path and adapted to be operated by the discharge current of said condenser, means controlled by said relay for closing said discharge path until said relay restoring and locking means has been released and for a predetermined period of time thereafter thereby to additionally

7
scharge the condenser, a device adapted to measure a predetermined interval of time in excess of the discharge time of the condenser, said device being connected to said relay and operated thereby, a mine firing circuit, and means on said device for closing said mine firing circuit when the time delay device has measured said predetermined interval of time in response to a second changing magnetic condition within said field sensed by said sensing means while the condenser is being charged and before the charge on the condenser has become sufficient to operate the relay restoring and locking means.

7. In a marine mine of the character disclosed, in combination, a mine firing mechanism disposed within a magnetic field, means in said firing mechanism for sensing in succession a plurality of changing conditions in said field during different intervals of time, a relay connected to said sensing means and adapted to be operated thereby as a changing condition is sensed, condenser means controlled by said relay for rendering the relay unresponsive to said sensing means for a predetermined period of time intermediate two of said time intervals when a changing magnetic condition has been sensed within the first of said intervals, means controlled by said condenser for measuring said second interval whereby the time of occurrence of a second changing condition sensed by said sensing means is compared with said second interval, and means controlled by said relay for firing the mine selectively in accordance with said comparison whereby the mine is fired when the second changing condition is sensed within said second interval.

8. In a mine adapted to be disposed within a magnetic field, means for detecting changing magnetic conditions within said field, a first relay means responsive to detection of a changed magnetic condition by said first-named means, a condenser, circuit means including a source of potential for slowly charging said condenser, means

6
10
15
20
25
30
including a second relay connected in the discharge path circuit for said condenser for resetting and locking said relay means for a predetermined period of time, a third relay means, said last-named relay means being actuated by said relay means and operable to discharge said condenser, and time delay means energized by said first relay means for firing the mine whereby after detection of an initial change in the magnetic field the first relay means is rendered unresponsive to a second change in the magnetic field during said predetermined period of time and the mine is fired upon detection of a change in the magnetic field within the time interval required for charging said condenser after the expiration of said predetermined period of time.

9. In a submarine mine of the character disclosed disposed within a magnetic field, a sensitive relay and a second relay connected for operation thereby, detector circuit means including said sensitive relay for detecting in succession a plurality of changing magnetic conditions within said field occurring during different intervals of time, means including a normally charged condenser connected for controlled discharge of the condenser by said second relay for locking said sensitive relay in a released condition for a predetermined period of time intermediate two of said time intervals when a changing magnetic condition has been detected within the first of said intervals, and means including a time delay relay connected in series with said second relay for firing the mine when a changing magnetic condition within the field has been detected during the second one of said intervals.
